PUDDLING MACHINE

Stephen R. Blackwell, East St. Louis, Ill.

Application January 16, 1932, Serial No. 587,118

8 Claims. (Cl. 61—63)

This invention relates generally to puddling machines for saturating and settling earth in highways, railroad fills, levees, etc., the predominant object of the invention being to produce an improved machine of the type which includes water conductors that are arranged to penetrate the ground and discharge water thereinto and which will perform the function for which it is intended in a very efficient manner. The invention of the present application is an improvement on the machine disclosed in an application bearing Serial Number 515,391 filed in my name on February 12, 1931, the present invention including features which improve the structure and efficiency of the machine as disclosed in the earlier application.

Fig. 1 is a side elevation of the improved puddling machine.

Fig. 2 is a rear elevation of the machine illustrated in Fig. 1.

Fig. 3 is an enlarged fragmentary detail, partly in section and partly in elevation, showing one of the cylinders of the machine together with the valve means for controlling passage of water to and from said cylinder.

Fig. 4 is a fragmentary sectional view taken through one of the cylinders of the machine and illustrating parts associated therewith.

Fig. 5 is a fragmentary detail illustrating the means for indicating the depth to which the plungers have been moved.

Fig. 6 is an enlarged fragmentary sectional detail illustrating the means for indicating whether or not water is passing through certain conductors of the machine.

Fig. 7 is a side elevation showing the machine in a collapsed condition for transportation along highways.

Fig. 8 is an end view of the machine in the condition illustrated in Fig. 7.

Fig. 9 is a horizontal sectional detail illustrating the manner in which the cylinders are hingedly supported.

In the drawings, wherein is shown for the purpose of illustration, merely, one embodiment of the invention, A designates my improved puddling machine generally, said machine including a suitable supporting truck 1 provided with ground wheels 2 and having suitable connecting means 3, whereby said supporting truck may be attached to a tractor or other apparatus for moving the machine along a road when in use and for transporting same from place to place. The truck 1 includes a rectangular frame 4 produced preferably by assembled channel beams, and ex-

tended upwardly from said frame 4 is a plurality of supporting beams 5. At the upper ends of the supporting beams 5 is a pair of channel beams 6 which are spaced transversely of the machine and extend longitudinally thereof, as shown most clearly in Figs. 2 and 3, said beams being located above the opposite sides of the truck 1 as shown in the views referred to. The structure supported by the truck 1 has associated with it a plurality of bracing elements 7 which are secured to said truck and to beams of the structure so as to give to said structure the necessary rigidity.

Supported by the channel beams 6 and extended transversely of the machine is a pair of angle beams 8 and 8', the beam 8 being located at the front of the machine and the beam 8' being located at the rear of said machine. The angle beams 8 and 8' are each provided with a plurality of bearing portions 9 through each of which a circular opening is formed, these bearing portions preferably, though not necessarily, being located at opposite ends of the angle beams.

Supported by the angle beam 8 at the front of the machine is a plurality of cylinders 10, preferably a pair thereof, which in the normal use of the machine are disposed in substantially perpendicular positions with respect to the ground, and supported by the angle beam 8' at the rear of the machine is a plurality of similar cylinders 11, preferably three of such cylinders, which are likewise normally disposed in substantially perpendicular positions with respect to the ground. The cylinders 10 are directly supported by a tubular element 12 which is supported at its opposite ends by the bearings 9 of the angle beam 8. As will presently appear herein, the arrangement of the cylinders 10 with respect to the tubular element 12 is such that said cylinders may be adjusted transversely of the machine so as to position them in various spaced relations with respect to each other, the cylinders being slidable longitudinally with respect to the tubular element 12 for making of such adjustments.

The cylinders 11 are directly associated with tubular elements 13, 14, and 15 which are arranged in telescoping relation, as shown most clearly in Fig. 2. The telescoping elements 13, 14, and 15 are supported by the bearing elements 9 associated with the angle beam 8' at the rear of the machine, and because of the telescoping arrangement thereof the associated cylinders 11 may be adjusted transversely of the machine so as to locate said cylinders in various spaced relations. In adjusting the cylinders 11, ordinarily the intermediate cylinder will remain stationary and the

two outer cylinders will be adjusted transversely of the machine toward and from said intermediate cylinder. The telescoping tubular elements 13, 14, and 15 are maintained in their proper 5 positions transversely of the machine by a pin 15', which is extended through apertures formed in the walls of said tubular elements. These apertures are located in various positions so that the tubular elements may be fixed in various 10 positions to which they have been adjusted. The cylinders associated with the tubular element 12 are provided with like means for maintaining them in various positions.

The means for attaching the various cylinders 15 10 and 11 to the tubular elements 12, 13, 14, and 15 includes in association with each individual cylinder an upright element 16 which preferably is of channel cross-section, as shown in Fig. 9. Each element 16 is attached in any 20 suitable manner to the tubular element 12, 13, 14, or 15 with which it is associated, the manner of attaching said upright elements to said tubular elements preferably including suitable straps 25 17 which are secured to the upright elements and surround the tubular elements. The upright elements 16 are maintained in their proper perpendicular positions by suitable tie rods 18 comprised of telescoping tie rod sections, which render said tie rods adjustable as to length. Such adjustable 30 tie rods are necessary because of the adjustable arrangement of the cylinders transversely of the machine. The straps 17 associated with the two outer cylinders 11 are fixed to the associated tubular elements, while the straps associated with 35 the cylinders 10 and the intermediate cylinder 11 are slidably mounted on the associated tubular elements.

Hingedly attached to each of the upright elements 16 through the instrumentality of suitable 40 associated hinge elements 19 is a member 20 which, in the normal use of the machine, is arranged in a vertical position, as shown most clearly in Figs. 1, 3, and 9. Each member 20 has associated with it one of the cylinders 10 or 45 11. Preferably each member 20 is of substantially channel-shape in cross section, as shown in Fig. 9, and at the upper and lower ends thereof of side plates 21 are secured to the opposite side walls of said members 20. The side plates 21 are 50 preferably of tapered shape, and at their outer ends overlap the associated cylinder slightly. Each member includes also a bottom wall 22 and a top wall 23 which constitute rigid parts of 55 said member. Fastening devices 19' secure the members 20 to the elements 16.

The cylinders 10 and 11 of the improved machine include each a suitable elongated barrel 24 provided with screw-threaded portions at its opposite ends (Fig. 4), and these screw-threaded 60 portions receive annular flange elements 25 which are screwed thereon. The flange elements 25 have secured thereto outer flange elements 26, suitable fastening devices 27 being employed for securing the associated flange elements 25 and 26 65 together. Each cylinder is attached to the associated member 20 in a manner to permit said cylinder to move vertically to a slight degree with respect to said member 20, and the means for accomplishing this purpose comprises bolts 27 and 28 at the top and bottom, respectively, of 70 the cylinder which guide the cylinder during such movement.

The bolts 27 are extended through openings 75 formed in the flange elements 25 and 26 at the top of the cylinder and pass through openings in

the top wall 23 of the member 20, as shown in Fig. 5. Also these bolts are extended a substantial distance above the top face of the top flange element 26, and each thereof is provided with a suitable washer 29 which abuts against a nut 30 screwed on the upper end of the bolt. At the lower end of each bolt 27 an abutment in the form of a head portion or a nut is provided which contacts with the lower face of the top wall 23 of the member 20. Interposed between the washer 29 of each bolt 27 and the top face of the flange element 26 of the associated cylinder is an expansible coil spring 31 which exerts downward pressure against the cylinder. The bolts 28 at the lower end of each cylinder are secured to the flange elements 25 and 26 of said cylinder, as shown in Fig. 5. In other words, a shoulder 28' at the upper end of a lower reduced portion 32 of each bolt contacts with the top face of the lower flange element 25 of the cylinder, and a nut 33 is screwed on the lower screw-threaded end of said reduced portion 32 and contacts with the lower face of the lower flange element 26. The upper portion of each bolt 28 passes through an aperture formed 100 through the bottom wall 22 of the associated member 20, and an abutment 34 in the form of a head portion or nut is located at the upper end of the bolt.

In view of the arrangement just described, it 105 is obvious that each cylinder may move vertically with respect to the associated member 20. It is also plain that the coil springs 31 resist upward movement of the cylinders and tend to maintain said cylinders in their lowered positions.

Arranged for reciprocatory movement within each cylinder 10 and 11 is a piston 35 which has associated with it a tubular element 36 (Fig. 4) that extends downwardly from said piston. The piston 35 comprises a main body portion 36' which is provided with a central opening 37 through which the tubular element 36 extends, said opening having a flared upper portion 38 which receives a correspondingly shaped upper portion 39 of the tubular element 36. The piston includes 110 a top element 40 which is secured to the main body portion 36' of the piston by suitable fastening devices 41, and said top element is provided with a plurality of apertures 42 which communicate with the passageway through the tubular 115 element 36. The main body portion is provided with an annular flange portion 43 at the lower face thereof, and the top element is provided with a corresponding portion which is in vertical alignment with respect to said annular flange portion 120 43. Interposed between said portions of the main body portion and the top element of the piston is a plurality of annular packing rings 44 which serve to prevent unnecessary leakage of fluid past 125 the piston 35.

At the lower end of each cylinder the flange element 26 thereof is provided with an opening 45 formed therethrough, and the lower portion of this opening is enlarged to provide a cavity 46 having a screw-threaded wall. The tubular element 36 extends through the opening 45, as shown in Fig. 4, and packing material 47 is introduced into the cavity 46 in such manner that it surrounds the tubular element. The packing material referred to is compressed about the tubular element by a gland 48 which is screwed into the cavity 46, whereby a fluid-tight joint is provided at the point where the tubular element passes through the opening 45. The gland 48 at its lower end is provided with a cavity 49 as shown 130

in Fig. 4 into which the lower end portion of the tubular element 36 is drawn when the piston is in the upper part of the cylinder. The lower end portion of the tubular element is internally screw-threaded and said screw-threaded portion receives the screw-threaded upper end portion of a head or jet element 50. By providing screw-threaded means for attaching the head 50 to the lower end of the associated tubular element 36, said head is rendered readily removable, and this arrangement is an important feature of the present invention, as will presently more fully appear.

As illustrated most clearly in Figs. 4 and 5, the machine includes means for indicating the location of the head 50 of each cylinder. In other words, it is essential in the operation of the machine that the operator know to what depth the heads 50 have penetrated the ground, and this information is given by the position of the weights 51, one of which is shown in Fig. 5. Each of the weights referred to is arranged for vertical movement within one of the members 20, and each weight is attached to one end of a flexible element 52 which extends over a pulley 53 mounted at the top of the associated cylinder, and passes through an opening formed in the flange element 26 of said cylinder into the cylinder. The end of the flexible element 52 within the cylinder is loosely attached to the piston 35 through the instrumentality of a bolt 54 which is mounted in an opening formed in the top element 40 of said piston so as to permit said bolt to move vertically with respect to said top element. The inner end of the flexible element 52 is attached to said bolt and the bolt is provided with abutments at its opposite ends in the form of a head 54^a and a nut 54^b which limit movement of the bolt with respect to the top element 26. Because of the lost motion at the bolt 54 of each cylinder, the head 50 of such cylinder may move downwardly to the surface of the ground before the associated weight 51 starts to move. In this way only the actual distance of penetration of the head in the ground is indicated by the movement of the weight as the weight is not moved during the preliminary movement of the piston before the lower end of the head 50 contacts with the ground.

The top flange element 26 of each of the cylinders 10 and 11 is provided with a passageway 55 into the outer end portion of which a nipple 56 is screwed (Fig. 4), the inner end of said passageway communicating with the interior of the cylinder. Also the lower flange element 26 of each cylinder is provided with a similar passageway 57 which communicates at its inner end with the interior of the cylinder and has a nipple 58 screwed into its outer end portion. In like manner the gland 48 is provided with an opening 59 formed in the wall of the cavity 49 thereof which receives a nipple 60.

The nipple 58 of each cylinder has associated with it a valve 61. The housing of this valve is preferably screwed on said nipple, as shown most clearly in Fig. 4, the opposite end of said valve housing having a nipple 62 screwed thereinto which communicates through the valve housing with the nipple 58. The interior of the valve housing is divided by a partition 63 into a cavity 64, which communicates directly with the nipple 58, and a cavity 65, which communicates directly with the nipple 62, and these cavities are placed in communication with each other by an opening 66 formed in the partition 63. Each valve 61 includes also a valve head 67 which is mounted on a valve stem 68, said valve stem being sup-

ported by an element 70 fixed to the element 20 of the associated cylinder. The valve stem is extended through an opening formed in the element 70, and coil springs 71 and 72 are arranged above and below said element, as shown most clearly in Fig. 4. The coil spring 71 contacts at its upper end with the lower face of the element 70 and at its lower end with a washer 73 mounted on the valve stem 68, while the coil spring 72 contacts at its lower end with the upper face of the element 70 and at its upper end with a washer 74 that contacts with a nut 75 screwed on the upper end of the valve stem 68. In view of this arrangement it is obvious that the valve stem 68 is supported by the element 70 in such manner that it is capable of slight vertical movement with respect thereto.

It has been heretofore stated herein that the cylinders of the improved machine are capable of slight vertical movement with respect to the associated elements 20, and because the valves 61 are secured to and move with the cylinders, said valves are subject to like movement. It is plain, therefore, that when the cylinders are moved vertically in a manner to be hereinafter set forth, the housings of the valves 61 will also move vertically and such vertical movement of the valve housings will cause the openings 66 in the partitions 63 of the valve housings to move to elevated positions where said openings will be closed by the valve heads 67.

Hingedly supported by the frame of the machine at the point designated by the reference character 75 is a structure 76 which supports a plurality of valves, said plurality of valves being arranged in units, and one unit being associated with each individual cylinder of the machine so that passage of water to and from said cylinders may be controlled.

In Fig. 3 I illustrate the valve unit associated with one of the cylinders, and because each cylinder is provided with a like valve unit, description of the unit illustrated will suffice for all of the units.

The valve unit of each cylinder includes an inlet conductor 77 to which a hose or other suitable conducting element 78 is attached for the purpose of conducting water from a suitable source of supply to the inlet conductor 77. The inlet conductor 77 is connected by a suitable fitting 79 to conductors 80 and 81 which extend in opposite directions from the inlet conductor 77, this fitting 79 also having connected to it a conductor 82 which connects the unit illustrated in Fig. 3 to the next adjacent unit (not shown) and serves as an inlet conductor for the latter unit. The conductor 80 has connected to it through the instrumentality of a suitable fitting 83 a nipple 84, and this nipple is connected, preferably by means of a suitable flexible conductor 85, to the nipple 56 at the upper end of the associated cylinder. Also, the upper end of the conductor 80 is connected by a suitable fitting 86 to a conductor 87, which conductor at its opposite end is connected to the nipple 60 associated with the gland 48 of the associated cylinder.

The conductor 81 is provided with a fitting 88 which has connected thereto a flexible conductor 89, said flexible conductor 89 being connected at its opposite end to the nipple 62 shown most clearly in Fig. 4. At its lower end the conductor 81 is provided with a fitting 90 which places said conductor 81 in communication with a conductor 91, the latter conductor serving as a discharge or outlet conductor through which water passes

which is being conducted away from the machine. The valve unit includes a by-pass 92 which is connected to the fitting 88 and to a fitting associated with the discharge conductor 91 whereby 5 said discharge conductor is arranged in communication with the conductor 81 through said by-pass.

The valves of the valve unit illustrated in Fig. 3 include a valve 93 associated with the conductor 80 and located between the fittings 79 and 83, and a valve 94 associated with said conductor 80 and located between the fittings 83 and 86. Also valves 95 and 96 are associated with the conductor 81, the valve 95 being located between the fitting 15 79 and the fitting 88, while the valve 96 is located between said fitting 88 and the fitting 90. Finally, the by-pass 92 has a valve 97 associated therewith, as shown clearly in Fig. 3.

In the operation thereof, my improved apparatus is transported to the location where it is to be used and the cylinders are raised to their perpendicular positions and are adjusted transversely of the machine so as to set said cylinders in the desired spaced relation. The various tie rods are 20 then secured in place so as to fix the cylinders in the positions to which they have been adjusted. The supporting structure 76 which supports the valve units is then elevated and secured in place by the supporting elements associated therewith, 25 after which the various flexible conductors which are associated with said valve units are connected to the elements with which they are associated.

With the parts referred to assembled as described, the machine is ready for use and the first 30 operation (after water has been introduced below the pistons) is to open the valves 93 of the various valve units. This will cause water which is conducted from a source of supply to the valve units by the conductor 78 to pass through the conductors 80 of the various valve units and through the conductors 85 leading from said conductors 80 to the upper ends of the various cylinders. At this time the valves 94 and 95 are closed so that no water may pass through said valves. 40 Part of the water which passes into the upper ends of the cylinders acts against the upper faces of the pistons within said cylinders, and the remainder of said water passes downwardly through the tubular elements 36 associated with the cylinders and is discharged from the orifices 50' at the lower ends of the heads 50 located at the lower ends of said tubular elements. The pressure of the water exerted against the upper faces of the pistons will force said pistons to move downwardly 45 through the cylinders, such downward movement being maintained at a slow and continuous rate of speed by manipulation of the valves 93, 96, and 97. The flow of the water as just described is indicated by the solid arrows in Fig. 3. As the 50 pistons are moved downwardly as described, the heads 50 which are pointed as shown in Fig. 4 are forced slowly and continuously through the ground, while water is being discharged from the orifices 50' thereof, with the result that the ground through and adjacent to which the heads 55 pass will be thoroughly saturated.

During downward movement of the pistons as described, any water which previously was introduced into the cylinders below the pistons, as and 60 for a purpose to be hereinafter described, will be forced out of the cylinders by the downwardly moving pistons, said water moving through the passageways 57, valves 61, conductors 89, and either through the conductors 81 or by-passes 92 65 to the discharge conductor 91, by which said wa-

ter will be conducted to the source of disposition thereof. The water which passes from the conductors 89 to the conductors 91 is controlled either by the valves 96 or the valves 97, the valves 97 being employed to control passage of such water when slow movement of the pistons is desired and the valves 96 being used when more rapid movement of said pistons is wanted. The valves 96 and 97 are, of course, constructed so as to obtain the difference in speed of movement of the pistons referred to. 80

When the pistons reach their lowermost points of movement and it is desired to reverse the direction of travel thereof the valves 93 are closed and the valves 95 are opened. This will cause water to pass from the inlet conductor 78, through portions of the conductors 81, and through the conductors 89 and valves 61 into the lower ends of the cylinders. At this time the valves 96 and 97 are closed and the valves 94 are open. The water which is forced into the lower ends of the cylinders will move the pistons upwardly, with the result that the water above the pistons which does not pass downwardly through the tubular elements 36 will be forced through conductors 85. 90 This last-mentioned water then passes through the valves 94 and flows through the conductors 87 to the cavities 49 within the glands 48 into which cavities said water is discharged to wash mud from the upwardly moving tubular elements 36 100 and from the heads 50 associated therewith. In Fig. 3 the direction of flow of the water when the piston is moving upwardly is indicated by the dotted arrows.

It is important to note that when the tubular elements 36 and heads 50 are forced downwardly through the ground there is no washing away of the ground by the water discharged from the orifices 50' of said heads. Instead, the heads 50 are forced cleanly through the ground, with the 110 result that the walls of the holes made by the heads will contact closely with the outer faces of the tubular elements 36, whereby the portions of the ground adjacent to said outer faces of the tubular elements will serve as stuffing boxes which 115 will prevent upward movement of the water discharged by the heads 50 through the holes produced by said heads. Also, as already stated, the movement of the heads 50 is continuous, hence there will be no washing away of the ground by 120 said water, but rather a gradual saturation of the ground as the heads 50 pass downwardly there-through.

It frequently happens that the heads 50 during downward movement thereof encounter unyielding objects below the surface of the ground, rocks for instance, which are sufficient to arrest downward movement of the heads. When this happens the water pressure will build up above the pistons until the cylinders are moved upwardly 130 with respect to the members 20 by which they are supported, the bolts 27 and 28 permitting such movement. This will cause the housings of the valves 61 to move to elevated points where the valve heads 67 will close the openings 66 and 135 thereby prevent passage of water through said valve housings. Thus the pistons will be locked by the water trapped above and below same in stationary positions, and the water being discharged from the orifices of the heads 50 will 140 saturate the ground around the obstruction until it may be displaced by the heads. When the obstruction yields because of the thorough saturation of the ground thereabout, the weight of the cylinders plus the downward exertion of the coil 145 150

springs 31 will cause the cylinders to move downwardly to their normal positions, when the valves 61 will again be in opened position and the normal operation of the apparatus will be resumed.

5 An important feature in connection with the valves 61 is that if desired they may be opened by reversing the direction of flow of the water; that is, by causing water to flow as indicated by the arrows in Fig. 4. This will have the effect of 10 moving the valve heads 67 upwardly against the tension of the coil springs 71 so as to open the valves.

When particularly deep holes are to be produced the apparatus is operated in the manner described to produce holes of the usual depth. 15 The pistons are then moved upwardly so as to withdraw the tubular elements 36 of the pistons and the associated heads 50 from the holes, after which the heads are removed from the tubular 20 elements and the cylinders are swung on their hinges 19 to the position shown in Fig. 9, wherein H designates a hole. An additional length of the tubular element with a head fixed to the lower end thereof is then introduced into each hole and this additional length of tubular element is 25 screwed on the lower end of the tubular element 36 associated with the piston after the cylinder has been returned to its proper position above the hole, whereupon the operation of the machine 30 may be continued in the usual manner.

Preferably I provide the improved machine with a suitable settling basin 100, so that rocks and other foreign matter is prevented from passing into the conductors of the machine. Also, the fact 35 that the heads 50 are removable permits of these heads being removed for cleaning purposes if small particles of foreign matter do find their way into said heads.

In order that the operator of the machine may 40 know at all times when water is flowing through the conductors 85 to the upper ends of the cylinders, I provide indicating devices 101 (Fig. 6) which are associated with the fittings 83 of the various valve units. This device comprises a 45 disk 102 mounted on a stem 103, said stem being supported for rotary motion, as shown in Fig. 6. The stem 103 has fixed thereto an element 104 provided with spiral vanes 105. When water is 50 passing through the fitting 83 said water will act on the spiral vanes 105 of the element 104 in a manner to rotate the stem 103 and the disk 102, and such rotation of the disk will indicate to the operator that water is flowing to the upper ends of the cylinders.

55 When it is desired to transport the machine from place to place the flexible conductors and the tie rods are detached and the cylinders are adjusted inwardly and are moved to horizontal positions, as shown in Figs. 7 and 8, said cylinders during such movement being pivoted about the tubular elements 12, 13, 14, and 15 by which they are supported. The machine may then be transported along roads without fear that the 60 dimensions thereof would be objectionable to the authorities having charge of traffic moving over said roads. In moving the cylinders to horizontal positions the tubular elements associated with the two outer cylinders 11 rotate with the cylinders, while in the case of the intermediate cylinder 65 11 and the cylinders 10 the associated tubular elements are maintained stationary and the cylinders rotate about said tubular elements.

70 It sometimes happens that when obstructions such as rocks are encountered below the surface 75 of the ground, as already explained, the weight

of the cylinders plus the exertion of the springs 31 will not displace said obstructions after the ground about the obstructions has been thoroughly saturated. For this contingency I provide means for opening the valves 61 by hand, so as to permit water pressure above the pistons to aid in forcing the heads 50 downwardly so as to displace the obstruction. The means referred to includes rods 106 which are pivotally connected to the elements 70 associated with the various valves 61 and which extend to the position of the operator, where they are provided with grip portions 106'. The elements 70 are each pivoted at 80 107, and when the rods 106 are pulled longitudinally by the operator, said elements will be moved about their pivots so as to draw the valve members 67 away from their seats. The water passing through the conductors 85 to the tops of the cylinders will then aid in forcing the heads 50 downwardly so as to displace the obstructions. To limit downward movement of the valve members 67 when they are manually operated stops 70' are provided.

In order to maintain the pistons 85 in their elevated positions when all water pressure is removed from the cylinders, I provide caps 108 (Fig. 4) which are screwed on the lower ends of the glands 48 and provide abutments with which the heads 50 contact so as to prevent downward movement of said heads.

I claim:

1. A puddling machine comprising a supporting structure, a plurality of cylinders associated with said supporting structure, pistons arranged within said cylinders and having ground-penetrating means associated therewith, means for conducting and controlling passage of piston-actuating water to and from said cylinder, and means whereby said cylinders may be adjusted relatively to each other and transversely of the puddling machine, the last-mentioned means including telescoping elements by which said cylinders are supported.

2. A puddling machine comprising a supporting structure, a plurality of cylinders associated with said supporting structure, pistons arranged within said cylinders and having ground-penetrating means associated therewith, means for conducting and controlling passage of piston-actuating water to and from said cylinder, and means whereby said cylinders may be subjected to pivotal movement and adjusted relatively to each other and transversely of the puddling machine, the last-mentioned means including telescoping elements by which said cylinders are supported.

3. A puddling machine comprising a supporting structure, a plurality of cylinders associated with said supporting structure, pistons arranged within said cylinders and having ground-penetrating means associated therewith, means for conducting and controlling passage of piston-actuating water to and from said cylinders, means whereby said cylinders may be adjusted relatively to each other and transversely of the puddling machine, the last-mentioned means including telescoping elements by which said cylinders are supported, and adjustable means for securing said cylinders in their normal operating positions.

4. A puddling machine comprising a supporting structure, a cylinder associated with said supporting structure, a piston arranged for reciprocatory movement within said cylinder, ground-penetrating means associated with said piston, means whereby said cylinder may be sub-

jected to straight line movement with respect to a portion of said supporting structure, a valve arranged for operation in response to straight line movement of said cylinder, and means for conducting and controlling passage of piston-actuating water into and from said cylinder.

5. A puddling machine comprising a supporting structure, a cylinder associated with said supporting structure, a piston arranged for reciprocatory movement within said cylinder, ground-penetrating means associated with said piston, means whereby said cylinder may be subjected to straight line movement with respect to a portion of said supporting structure, means which 10 tends to subject said cylinder to straight line movement in one direction, a valve arranged for operation in response to straight line movement of said cylinder, and means for conducting and controlling passage of piston-actuating water 15 into and from said cylinder.

6. A puddling machine comprising a supporting structure, a cylinder associated with said supporting structure, a piston arranged for reciprocatory movement within said cylinder, ground-penetrating means associated with said piston, means whereby said cylinder may be subjected to straight line movement with respect to a portion of said supporting structure, means which tends to subject said cylinder to straight 20 line movement in one direction, a valve arranged for operation in response to straight line movement of said cylinder, and means for conducting and controlling passage of piston-actuating water 25 into and from said cylinder.

35

7. A puddling machine comprising a supporting structure, a cylinder associated with said supporting structure, a piston arranged for reciprocatory movement within said cylinder, ground-penetrating means associated with said piston, 80 means whereby said cylinder may be subjected to straight line movement with respect to a portion of said supporting structure, a valve arranged for operation in response to straight line movement of said cylinder, and means for conducting and controlling passage of piston-actuating water into and from said cylinder, said valve comprising a valve housing movable with said cylinder and with respect to a valve element which opens and closes said valve housing to 85 passage of water therethrough.

8. A puddling machine comprising a supporting structure, a cylinder associated with said supporting structure, a piston arranged for reciprocatory movement within said cylinder, ground-penetrating means associated with said piston, 90 means whereby said cylinder may be subjected to straight line movement with respect to a portion of said supporting structure, a valve arranged so as to be closed in response to straight 95 line movement of the cylinder in one direction, means for manually opening said valve when same has been closed by movement of the cylinder, and means for conducting and controlling passage of piston-actuating water into and from 100 said cylinder.
